UNITED STATES PATENT OFFICE.

HOWARD M. CLEMMER, OF GASTONIA, NORTH CAROLINA.

METAL SHINGLE.

1,072,825.

Specification of Letters Patent. Patented Sept. 9, 1913.

Application filed November 25, 1912. Serial No. 733,491.

To all whom it may concern:

Be it known that I, HOWARD M. CLEMMER, a citizen of the United States, residing at Gastonia, in the county of Gaston and State 5 of North Carolina, have invented a new and useful Metal Shingle, of which the following is a specification.

This invention relates to shingles and more particularly to those which are made 10 from metal.

An object is to provide a metallic shingle which may be easily and readily secured in place, will interlock with the adjoining shingles to form a roof or side wall which will 15 be substantially water-tight.

With the foregoing and other objects in view which will appear as the description proceeds, the invention resides in the combination and arrangement of parts and in 20 the details of construction hereinafter described and claimed, it being understood that changes in the precise embodiment of the invention herein disclosed, can be made within the scope of what is claimed, without 25 departing from the spirit of the invention.

In the drawings accompanying this specification and forming a part thereof, the preferable form of my invention is illustrated, in which:

30 Figure 1 is a plan view of my improved metallic shingle. Fig. 2 is a cross sectional view thereof, taken on the line 2—2 of Fig. 1, and Fig. 3 is a cross sectional view thereof, taken on the line 3—3 of Fig. 1.

35 Referring to the drawings in which similar reference numerals designate corresponding parts throughout the several views, 1 is the shingle body portion which is beveled to form the central guide portion 2 40 which is for the purpose of deflecting the water toward the central portion of the shingle and away from the interlapping edges.

The four edges of the shingle are designated by the letters A, B, C and D, respectively. The edge A of one shingle interlapping and coacting with edge C of the adjacent shingle to thereby form a continuous roofing material. In a like manner, the edge 50 B will coact with the edge D of the adjacent shingle thereto, the various edges A, B, C and D being so constructed as to securely lock the various shingles in position as well as interlap and thereby cover the 55 portion which is nailed to the roof sheathing.

The edge A comprises an upward and inclined portion 3, a horizontal portion 4, a second horizontal portion 5 offset therefrom and connected thereto by means of the beveled edge 6. The numeral 7 designates a similarly beveled edge and terminates in the vertically extending portion 8 which is bent inward to form the horizontal inclined edge 9. The edge C is adapted to interlock with the edge A just described and is composed of the horizontal flange 10 through which are driven the securing nails 11. Integral with the flange 10 is the upwardly inclined portion 12 which is similarly inclined as the 70 wall 3 with which it is adapted to contact. The upper portion of this wall 12 is bent downward as at 13, horizontal as at 14, vertical as at 15 and is then composed of the portions 6', 5', 7', 8', and 9' which are similar though relatively smaller, than the sections 5, 6, 7, 8 and 9 of the edge A. The portion 9' is connected with the body of the shingle by the downwardly extending wall 16. From the foregoing it will be apparent 80 that the portions 15, 6', 5', 7', 8', 9' and 16 will constitute a heptagon bead and the portions 12 and 13 will form a second bead spaced a distance therefrom by the wall 14, which will constitute a channel or gutter for 85 such water as may be driven in between and beyond the heptagon bead. The U-shaped bead formed by the walls 12 and 13, and the heptagon bead are adapted to lie within the edge A, as illustrated in Fig. 3.

90 The top and bottom edges of the shingles B and D respectively, are also adapted to coact to form a water tight joint. The edge B is formed with the beaded portion composed of the walls 17, 18 and 19. A U-shaped ridge or bead 20 is spaced therefrom by the wall 21 and an offset flange 22 is spaced from the beaded portion 20 by the portion 23. The edge D is formed with a raised portion 17', 18', 19', which will coact with the similar unprimed numerals of the edge B, a second bead 20' being spaced from an oblique portion 21', the manner in which the edges coact being more clearly illustrated at the upper portion of Fig. 2. The portion or wall 23 is adapted to be rigidly held to the roof sheathing by suitable nails or other securing means and by reason of the coacting interlapping edges the water 100 will be prevented from reaching the so 105 formed apertures.

110 From the foregoing it will be readily ap-

parent that my improved shingle construction will be easy and cheap to manufacture, being one which may be readily stamped from sheet metal, the lowered portion 2 of 5 the body 1 tending to direct the water toward the central portion of the shingle and away from the interlapping edges, and the interlapping edges being so formed that it will be substantially impossible for any 10 water to leak through and beyond the interlapping edges by reason of the channel or gutter formed between the two beaded portions as hereinbefore mentioned. The upper and lower edges B and D are so constructed 15 as to be readily interlocked and so coacting as to render the entire roofing substantially waterproof. The result of such features combine to form an extremely useful and desirable roofing material.

20 Having thus fully described the construction and pointed out the particular advantages inherent thereto, what I claim to be new and original with me is:—

25 A metallic shingle comprising an upper edge formed with an upturned end, a nailing flange connected thereto, a U-shaped bead connected to said nailing flange, a wide shallow bead spaced from said U-shaped bead with one wall thereof inclined, the 30 lower edge of said shingle adapted to coact with the upper edge of a sub-adjacent shingle and comprises a wide shallow bead

with an inclined wall, and a second bead of arcuated contour adapted to engage one side of the said U-shaped bead and to receive 35 therein the upturned end of the upper edge of the sub-adjacent shingle, and with a side edge comprising a flat nail receiving flange, a U-shaped bead spaced a distance therefrom and provided with an inwardly extending side wall, a polygonal bead with a reentrant angle spaced a distance from said U-shaped bead, the other edge of said shingle provided with an inwardly turned end adapted to enter the reentrant angle and coact with the side edge of the horizontally adjacent shingle, and an upstanding groove adapted to house therein the said U-shaped bead and polygonal bead, said groove provided with an inclined inner wall adapted to 45 contact with the inclined side wall of the U-shaped bead, the said shingle adapted to be nailed to the roof sheathing along the upper and one side edge thereof and adapted to interlock with an adjacent shingle along 50 a remote side edge.

In testimony that I claim the foregoing as my own, I have hereto affixed my signature in the presence of two witnesses.

HOWARD M. CLEMMER.
